UNITED STATES PATENT OFFICE.

ROBERT BRAGG, OF DAYTON, OHIO, ASSIGNOR OF THREE-FOURTHS TO
WILLIAM F. CHAMBERLIN, S. SCOVEL CHAMBERLIN, AND WILLARD
D. CHAMBERLIN, OF SAME PLACE.

CRANK-PIN.

SPECIFICATION forming part of Letters Patent No. 572,497, dated December 1, 1896.

Application filed April 20, 1896. Serial No. 588,347. (No model.)

To all whom it may concern:

Be it known that I, ROBERT BRAGG, a subject of the Queen of Great Britain, residing at Dayton, in the county of Montgomery, State 5 of Ohio, have invented certain new and useful Improvements in Crank-Pins and Means for Securing the Same in Place; and I do hereby declare the following to be a full, clear, and exact description of the same, reference being 10 had to the accompanying drawings, forming a part of this specification, and the letters of reference marked thereon.

Much difficulty has been experienced in removing and renewing worn and broken crank-pins, particularly the crank-pins of locomotive drive-wheels, owing to the fact that when 15 said pins were secured in place in the ordinary manner it necessitated the removal of the entire wheel from the locomotive, the 20 heating of the same to loosen the pin, and the shrinking in of a new pin. The expense of such an operation is very great; and it is the object of my present invention to provide a crank-pin and means for holding the same in 25 place which will permit of the ready removal or insertion of the pin while the wheels are in place and at the same time afford a rigid structure which will withstand shock and wear of usage as well if not better than the 30 ordinary arrangement wherein the pins are secured by shrinkage of the metal of the wheel on the same.

Referring to the accompanying drawings, Figure 1 is a vertical section through a portion 35 of the drive-wheel of a locomotive, showing a crank-pin applied in accordance with my present invention. Fig. 2 is a detail, on an enlarged scale, of the crank-pin alone. Fig. 3 is a similar view of one of the conical 40 clamping-pieces; and Fig. 4 is a similar view of the locking-nuts, showing the set-screw for holding the jam-nut in its fixed position of adjustment.

Like letters of reference in the several figures indicate the same parts.

In carrying my invention into practice instead of forming a straight cylindrical hole through the body of the wheel or crank, if it is not a wheel, for the reception of the crank-pin

base I now form a conical aperture through 50 the wheel or crank, as the case may be, having its smallest diameter at the outer side of the wheel or crank, and in this conical aperture I fit sectional clamping-blocks made conical on the outer surface to accurately fit the 55 conical aperture, which clamping-blocks are formed with a cylindrical central bore, into which the end of the crank-pin is fitted and adapted to be clamped by forcing the blocks into the conical aperture, as will be readily 60 understood.

Referring to said drawings, the letter A indicates a section of the drive-wheel, and a the conical aperture formed therein at the proper distance from the axis or center of 65 rotation to give the desired leverage to the crank. Fitting in this conical aperture are preferably two clamping-blocks B B, made conical on their outer surface and ground to accurately fit the aperture. A cylindrical aperture b is formed through these clamping-blocks, and when in place they should be so proportioned that a very narrow space will be left between them. In other words, instead 70 of being truly semicylindrical in cross-section they are slightly less than semicylindrical, and at their rear or larger ends they are preferably provided with a countersink or enlarged bore C, for a purpose which will presently appear.

The crank-pin at the outer end is formed in an ordinary manner with a bearing D for the connecting-rod and collars d d' for holding the connecting-rod in position. The collar d' is adapted to seat against the face of the drive-wheel, or, if desired, to be recessed into the same slightly, and projecting rearwardly from this collar is the shank portion D', which is adapted to be accurately fitted in and clamped by the clamping-blocks B. The extreme rear 85 end of the shank on the crank-pin is threaded for the reception of a locking-nut E and also for the reception of the jam-nut E' for preventing the loosening of the locking-nut when the pin is subjected to strains or shock.

The nut or nuts applied to the rear end of the shank of the crank-pin are adapted to seat into the recess C in the clamping-blocks, and

when set up draw the collar d' firmly against the drive-wheel and tend to force the clamping-blocks farther into the conical recess, the result of which action is that the shank of the 5 crank-pin is clamped firmly and held accurately in a centered position. The countersinking of the nuts overcomes any liability of the nuts striking any part of the machinery, and in effect presents the same appearance as 10 a wheel having a crank-pin applied in the ordinary way.

As an additional precaution against the possible loosening of the jam-nut I provide it with a set-screw F at one side adapted to pass 15 through the nut and coöperate with the threads on the shank of the crank-pin.

The parts when adjusted in position should be so proportioned that the split box or clamping-block should lack just a little of coming 20 up to the collar on the pin, so that it will not strike and prevent an effective clamping action on the shank.

Practice has demonstrated that the crank-pin mounted in the wheel in accordance with 25 the present invention will be absolutely rigid, and by setting up the nuts with even a slight pressure it is clamped so firmly as to preclude all possibility of its being wrenched or turned in its bearing under the action of the connecting-rod, although, as an additional protection 30 against its being turned, it is preferable that the securing-threads be so cut that any turning of the crank-pin will tend to draw the nuts more tightly into place when the locomotive is running forward.

While I have specifically described my invention as applied to a locomotive drive-wheel, it will be understood that the invention is equally applicable to any crank or 40 other machinery where it is desired to secure a crank-pin in place.

Having thus described my invention, what I claim as new is—

1. The combination with the crank or wheel having a conical aperture formed therein, of 45 a crank-pin seating against the crank or wheel at the smaller end of the aperture, conical clamping-blocks fitted in said aperture and having a central bore fitting the shank of the crank-pin and a locking-nut on the rear end 50 of the crank-pin bearing against the larger end of the clamping-blocks; substantially as described.

2. The combination with the crank or wheel having a conical aperture formed therein, and 55 a sectional clamping-block having its outer surface fitted to the conical aperture and a cylindrical internal aperture, a crank-pin having a collar seating against the crank or wheel at the smaller end of the aperture and a cylindrical shank extending through the aperture in the sectional clamping-block and a locking-nut screwing on the rear end of the crank-pin and coöperating with the sectional clamping-block to hold the parts in adjusted 60 position; substantially as described.

3. The combination with the crank or wheel having the conical aperture therein and the crank-pin seating against the crank or wheel at the smaller end of the aperture and having 70 the shank projecting through said aperture, of the split clamping-block surrounding said shank and having the external conical surface fitting the aperture and central enlarged recess at the rear end and the locking-nut 75 screwing on the shank of the crank-pin and seating in said recess; substantially as described.

ROBERT BRAGG.
